CONVEYER

Vincent A. Rayburn, Baltimore, Md., assignor to
 Western Electric Company, Incorporated, New
 York, N. Y., a corporation of New York

Application December 21, 1945, Serial No. 636,401

2 Claims. (Cl. 198—177)

1

This invention relates to conveyers, and has for its object the provision of new and improved conveyers.

A conveyer forming one embodiment of the invention comprises an article-carrying element, means for moving the article-carrying element, means for locking the article-carrying element in a predetermined position with respect to the moving means, and means for changing the position of the article-carrying element with respect to the moving means.

A complete understanding of the invention may be obtained from the following detailed description of a conveyer forming a specific embodiment thereof, when read in conjunction with the appended drawing, in which

Fig. 1 is a front elevation of a portion of a conveyer embodying the invention with portions thereof broken away;

Fig. 2 is a horizontal section taken along line 2—2 of Fig. 1;

Fig. 3 is an enlarged perspective view of a portion of the conveyer;

Fig. 4 is a front elevation of the conveyer;

Fig. 5 is a vertical section taken along line 5—5 of Fig. 4;

Fig. 6 is a horizontal section taken along line 6—6 of Fig. 4 with portions of the conveyor broken away, and

Fig. 7 is a vertical section taken along line 7—7 of Fig. 1.

Referring now in detail to the drawing, there is shown therein a hook assembly 10 (Fig. 1), which includes a hook 11 secured to a sleeve 12 mounted slidably and rotatably upon a shaft 15. A horn 13 is formed on the hook 11, and a catch 14 is fastened to the horn near the inner end thereof. The sleeve is supported upon the shaft by a two-lobe cylindrical cam 16 secured upon the lower end of the shaft, as viewed in Fig. 1. The cam 16 (Fig. 3) has formed thereon diametrically opposed lobes 17 and 18, and also is provided with diametrically opposed depressions 19 and 20, which are spaced 90° from the lobes 17 and 18.

A two-lobe cylindrical cam 21 formed on the lower end of the sleeve 12, as viewed in Fig. 1, is complementary to the cam 16 and includes lobes 22 and 23 (Fig. 4) and depressions 24 and 25. The cams 16 and 21 are self-meshing and the cam 21 is moved by gravity into mesh with the cam 16 whenever it has been moved out of mesh therewith and the sleeve 12 is free to rotate relative to the shaft 15. The cam 21 meshes with the cam 16 when the cam 21 is in either of two positions

2

spaced 180° apart, and when it is rotated over 90° from one of these positions, it will automatically fall into the other position in which it is designed to mesh with the cam 16. Thus, the horn 13 of the hook 11 normally points in one of two directions spaced 180° apart.

A clevis 26 (Fig. 5) fastened rigidly to the upper end of the shaft 15 is secured by a pivot pin 31 to a tang 32 secured rigidly to a conveyor chain 35. The chain is supported in a position between tracks 37—37 by supporting rollers 40—40 and may be advanced along the tracks by suitable advancing means (not shown). The clevis and the tang permit the shaft 15 to remain plumb regardless of the inclination of the tracks but prevent rotation of the shaft about its own axis. A counter-balance 39 (Fig. 1) is secured to the sleeve 12 and maintains the hook 11, when the hook is empty, in a position in which the horn 13 thereof is horizontal. When the cam 21 is in mesh with the cam 16, the horn points either in the direction the chain 35 (Fig. 5) advances the hook assembly 10 or in a direction opposite thereto.

A four-tooth pinion 41 (Figs. 1 and 2) formed on the upper end of the sleeve 12 has formed therein a counterbore 42, which is designed to provide clearance for the clevis 26 when the sleeve 12 is slid upwardly on the shaft 15, as viewed in Fig. 1. The pinion 41 is provided with teeth 45, 46, 47 and 48 (Figs. 2 and 6). A rack 50 (Figs. 4 and 6) is positioned below one of the tracks 37—37 and includes rack pins 51 and 52, which are spaced a predetermined distance apart and project from a base 55 of the rack. The pinion is so orientated with respect to the cams 16 and 21 that when the cams 16 and 21 intermesh, either the tooth 47 or the tooth 45 projects downwardly and slightly to the right, as viewed in Fig. 6.

In the operation of the conveyer described hereinabove, the chain 35 (Fig. 5) serves to move the hook assembly 10 toward the right, as viewed in Fig. 4. When the hook assembly is in a position similar to that designated position A, the hook 11 is in a position in which the picking up of a spool 56 is facilitated. The spool may be placed in the path of the horn 13 of the hook, and, as the hook is advanced toward the spool, the horn enters a hole 57 therein and carries the spool therewith. The catch 14 serves to prevent the spool from sliding off the horn and holds it in a position in which the center of gravity of the spool is aligned with the axis of the shaft 15.

As the hook assembly 10 is moved from position A to a position designated position B, the rack

pin 51 is engaged by the tooth 47 of the pinion 41 and tends to retard the movement of the tooth 47, and as the hook assembly continues to advance relative to the rack 50, the pinion is rotated in a clockwise direction, as viewed in Fig. 6. This also rotates the hook assembly 10 (Fig. 4) to position B, and as the hook assembly is so rotated, the lobes 22 and 23 of the cam 21 are moved out of engagement with the depressions 19 and 20 (Fig. 3), respectively, of the cam 16, and into engagement with and slightly over dead center with respect to the lobes 18 and 17, respectively, of the cam 16.

As the hook assembly 10 is rotated to position B, the sleeve 12 is rotated and slides upwardly upon the shaft 15, as viewed in Fig. 4, as the lobes 22 and 23 move into engagement with the lobes 18 and 17. The tooth 47 slides upwardly on the rack pin 51, which is long enough that the tooth 47 does not slide over the end thereof.

Since the tooth 47 is directed slightly forwardly as it approaches the rack pin 51, the rack pin 51 moves the pinion 41 through an angle of at least 90° while the tooth 47 is in engagement therewith. As the pinion is so rotated, the tooth 48 is moved to a position between the rack pins 51 and 52 and is engaged by the rack pin 52, which rotates the pinion further, whereby the lobes 22 and 23 of the cam 21 are moved out of dead center with respect to the lobes 18 and 17 of the cam 16. The lobes 22 and 23 then are forced by gravity downwardly, as viewed in Fig. 4, away from the lobes 18 and 17, and the sleeve 12 is rotated upon the shaft 15. The tooth 48 of the pinion strikes the rack pin 51 as it is so rotated, whereby the rotation of the hook assembly 10 is slowed down. The chain 35 continues to advance and moves the tooth 48 out of engagement with the rack pin 51. The hook assembly then continues to rotate by the interaction of the cams 16 and 21 until the cams intermesh, at which time the horn 13 points in a direction opposite to that in which the hook assembly is advanced.

When the hook 11 is in position C or a position similar thereto, the spool 56 may be removed therefrom merely by lifting the spool so that it clears the catch 14 and retarding the spool relative to the horn 13. After the spool 56 has been removed from the hook 11, another turner (not shown) identical with the turner 50 may be used to turn the hook assembly 10, 180° so that it is in a position similar to position A so that a spool similar to the spool 56 may be loaded thereon.

The above-described conveyer serves to convey hook assemblies similar to the hook assembly 10 along the tracks 37-37 in orientated positions with respect to the chain 35 (Fig. 5). The self-meshing cams 16 and 21 (Fig. 4) serve to lock the hook assembly either in a position in which the

5 horn 13 of the hook 11 points in the direction in which it is advanced, or in a position in which the horn points in a direction opposite to that in which it is advanced, so that the hook assembly cannot be accidentally turned to the wrong position. However, the hook may be turned surely and effectively by the turner 50. Thus, the horn 13 of the hook 11, depending upon its position relative to the tracks 37-37, is orientated suitably for picking up spools similar to the spool 56, or for depositing such spools.

What is claimed is:

1. A conveyer, which comprises a conveyer chain, means for guiding the chain along a predetermined path, a shaft depending from the chain, means for holding the shaft against rotation about its longitudinal axis, a sleeve mounted rotatably and slidably upon the shaft, a hook supported by the sleeve, and a pair of self-meshing cylindrical cams having no dwell portions and having two positions of rest, one of the cams being secured to the shaft and the other cam being secured to the sleeve.
2. A conveyer, which comprises a conveyer chain, means for guiding the chain along a predetermined path, a shaft pivotally secured to the conveyer chain, a hook, a sleeve rotatably and slidably mounted on the shaft for supporting the hook, a cylindrical cam having a pair of diametrically opposed lobes formed thereon and positioned on the bottom of the rod for securing the sleeve upon the rod, said cylindrical cam also being provided with depressions positioned between the lobes, a second cylindrical cam secured to the sleeve for intermeshing with the first-mentioned cylindrical cam to lock the sleeve in either of two positions spaced 180° apart, said cams having no dwell portions so that said second cylindrical cam falls automatically into mesh with the first-mentioned cylindrical cam if it is moved out of intermeshing engagement therewith, a four-lobe pinion secured to the sleeve, and a rack positioned in the path of the pinion for rotating the pinion to rotate the sleeve and move the 45 second cam out of intermeshing engagement with the first-mentioned cam.

VINCENT A. RAYBURN.
